UNITED STATES PATENT OFFICE.

WILLIAM MURRAY AND EDWARD C. BANTA, JR., OF BROOKLYN, NEW YORK.

TIME-RECORDER FOR TRUCKS.

1,256,586.

Specification of Letters Patent. Patented Feb. 19, 1918.

Application filed May 6, 1916. Serial No. 95,773.

To all whom it may concern:

Be it known that we, WILLIAM MURRAY and EDWARD C. BANTA, Jr., both citizens of the United States, and residents of the borough 5 of Brooklyn, county of Kings, city and State of New York, have jointly invented certain new and useful Improvements in Time-Recorders for Trucks, of which the following is a specification.

10 Our invention relates to time-recorders for use on vehicles, and particularly on automobile trucks, which make a great many trips every day and for this reason spend a good deal of time in loading and 15 unloading. The purpose of our invention is to provide an efficient device of this character, the operation of which will be largely automatical, and which will give a clear and complete record of all functions performed 20 in the course of a working day and of the time consumed in the performance of these various functions. Further advantages of our invention will be explained in the description following hereinafter, and the 25 novel features will be pointed out in the appended claims.

In the accompanying drawings, Figure 1 is an elevation, with parts in section, of our improved time-recorder; Fig. 2 is a top 30 view of the device, with the cover removed; Figs. 3, 4, 5 and 6 are vertical longitudinal sections, taken on lines 3—3, 4—4, 5—5, and 6—6 respectively of Fig. 2; Fig. 7 is a cross section taken on line 7—7 of Fig. 2; Fig. 8 is an end view of the various markers employed in our device, looking in the direction of the arrow 8 in Fig. 2; Fig. 9 is a detail horizontal section taken on line 9—9 35 of Fig. 3; Figs. 10 and 11 are a front view 40 and a side view respectively of a certain part shown in Fig. 3; Fig. 12 is a detail view of a lever shown in Fig. 3, looking in the direction of the arrow 12 in said Fig. 3; Fig. 13 is a small cross section of certain parts, taken 45 on line 13—13 of Fig. 6; Figs. 14 and 15 are detail views showing how the strip or sheet of paper on which the record is made, is secured to the drum carrying it; and Fig. 50 50 shows a portion of the sheet of paper on which our time-recorder records, and the manner in which such record is made.

Referring to the drawings, and particularly to Figs. 1, 2 and 7, a clock 20 mounted on a base 21 carries a gear 22 which 55 revolves with the small or hour-hand of the clock 20. In mesh with this gear 22 is an

other gear 23 whose diameter is double that of the gear 22, so that the speed of the gear 23 will be half that of the gear 22, that is to say, while gear 22 performs, with the 60 small hand of the clock, two revolutions in 24 hours, gear 23 will perform only one revolution in the same period. Gear 23 is mounted rigidly on a shaft 24 which is carried by, and revolves in, a U-shaped support 65 25 secured to the base plate 21 by screws 25'. Sleeves 26 with set screws 26' prevent axial movement of the shaft 24, while ball bearings 27 assist the rotary movement of the shaft 24 and gear 23 (Fig. 7). On the side 70 of the gear 23 opposite to the support 25, the shaft 24 carries, removably mounted thereon, a wheel 28 to the rim of which is fastened, by means of screws 28', a cylindrical plate 29. This plate forms a drum whose cylindrical surface is adapted to carry the strip 75 of paper on which our device is intended to record the various functions performed by the automobile truck or other vehicle, as will be described in detail below. By means of a key 24', the wheel 28 with the drum 29 is compelled to rotate with the shaft 24. For the purpose of securing the wheel 28 and drum 29 in the proper position, after the former has been slipped over the key 80 85 24', and to hold said wheel and drum against motion lengthwise of the shaft; we provide a lever 30 pivoted on the wheel at 30' and having its inner end pulled toward the shaft 24 by a spring 30''. The inner end of the lever 30 is formed with a notch 30* adapted to catch over the annular flange of a sleeve 31 secured to the shaft 24 by means of a set screw 31'.

The recording mechanism comprises preferably two superimposed strips of paper 32, 32' (Fig. 7), the lower one of which serves as the recording strip proper, while the upper one serves as a protection for the strip of carbon paper 32'' or the like interposed between them, by which any recording impression made on the upper strip will be traced on the lower or recording strip. Figs. 7, 14 and 15 show a simple way of securing the recording strip to the drum 29. At some point of its circumference (which may conveniently be the point where the two ends of the plate forming the drum meet), the drum is provided with a transverse slot 29' through which one end of the 100 105 recording strip 32 may be inserted and secured to the projection 29'' provided on the 110

inside of the drum on one side of the slot 29'. On the other side of the slot 29' the drum carries, likewise on its inner side, two pins 29* extending through slots 33' provided in a small plate 33. These slots 33' extend in a direction transverse to that of the slot 29', so that the plate 33 will be capable of a slight circumferential movement relatively to the drum, collars or nuts 10 on the pins 29* holding the plate 33 against the drum 29, while allowing such circumferential movement. A projection 33'' will facilitate the shifting of the plate 33. This latter is also provided with a slot 33* extending parallel to the slot 29' in the drum 29 and registering in one extreme position of the plate 33 with said slot 29', so that the free end of the recording strip (after it has been placed on the drum) can be inserted 15 through these two slots. A lateral shifting of the plate 33 to its other extreme position will then draw the recording strip tight around the drum and clamp its ends firmly between the plate 33 and the drum. Of course, when a protective strip (such as 32', Fig. 7) is used in conjunction with the recording strip, both strips would be secured at the same time by the clamping device just described.

As shown in Fig. 16, the recording strip is divided by lines running parallel to the drum axis into equal spaces or columns of which there are 24 on the whole strip, representing the 24 hours of the day; each of 20 these columns may be subdivided to indicate the half-hours, quarters of an hour and smaller subdivisions if desired, but for our purpose it will be sufficient to have these divisions indicated as shown in Fig. 16. The recording strip is further divided by lines running lengthwise of the strip, into five spaces or rows of equal width, for the purpose of marking therein the five different functions which our device is intended to 25 record, as will be described below.

The first one of the rows just referred to, (I), serves to record therein the speed at which the vehicle has been traveling at any time of the day or night, and incidentally thereto also the mileage. This is accomplished by the following mechanism shown in Figs. 1, 2 and 3: To the base 21 is secured a block 36 which forms a support for two plates 37, 37' standing upright on said 30 block and rigidly secured thereto by means of screws 38. These plates are held at the proper distance from each other by distance pieces 39, 39', 39'' and 39* alternating with thin partition strips 40, 41, and by screws 42. As shown in Fig. 4, the screws 38 press downwardly on a bar 38' resting on the lowermost screws 42. Through this whole structure extends a shaft 43 supported in the side plates 37, 37', and held against longitudinal 35 movement by a flange 43' on the outer side of the plate 37, and by a nut 43'' screwing on the end of the shaft on the outer side of the plate 37'. Adjacent to the flange 43', the shaft 43 carries a pinion or worm wheel 44 in mesh with a worm 45 on a shaft 46 70 journaled in bearings 47, 47' secured to the plate 37. This shaft 46 is operated from the wheel of the vehicle by any suitable means, as for instance by a flexible shaft 48, a one-way clutch being preferably provided so 75 that the shaft 46 will be operated only when the truck or other vehicle is traveling forward. Such clutch may consist, for instance, of a disk 46' secured to the shaft 46 and having teeth in mesh with those of a mating 80 disk 48' pressed toward the other disk by a spring 48'' engaging a sleeve on the disk 48' and a collar or head 46'' on the end of the shaft 46. The disk 48' is held to turn with the shaft 48, but allowed to move 85 lengthwise thereof, as by means of keys 48*. To further guard against accidental rotation of the shaft 46 in the wrong direction, we provide a pawl 49 carried by the plate 37 and engaging a ratchet wheel 49' on said 90 shaft.

Rigidly secured to that portion of the shaft 43 which is adjacent to the inner side of the plate 37, there is a disk 50 having a pin 50' arranged to engage, at times, a lever 51 pivoted at 51* between the plate 37 and the first partition strip 41 (Fig. 3). A spiral or coiled spring 52, secured to the lever 51 and to one of the distance pieces 39, normally holds the lever 51 against a stop 53. 95 The lever 51 is provided with slots 51', 51'' (Figs. 3 and 12), of which the slot 51'' will allow the pin 50' to pass without acting on the lever 51, while the other, 51', will allow the pin 50' to clear the lever 51 only after 100 the latter has been swung a distance on its pivot, against the tension of the spring 52. Pivoted on a pin 54 extending from the side plate 37 to the side plate 37', is a lever 55 normally held in its position of rest against 105 the stop 56 by a spring 57 carried by one of the distance pieces 39*. The end portion of the lever 55 adjacent to the stop 56 is forked and carries, pivotally connected therewith at 55', a short arm 58, whose narrow middle portion fits into the forked end of the lever 55. Normally a spring 58' will hold the arm 58 in the position shown in Fig. 3. Figs. 10 and 11 show detail views of the arm 58; it will be seen by reference to these figures and to Fig. 3, that the arm 58 can yield when swung on its pivot in one direction, against the tension of the spring 58', that is to say, its lower portion is capable of 115 swinging to the right in Fig. 3. It cannot swing, however, in the opposite direction, beyond the position shown in Fig. 3, owing to the fact that in this position the short horizontal faces 58'' bear against the lever 55; any effort exercised in this direction will 120 125 130

not swing the arm 58 with respect to the lever 55, but will swing the lever 55 on its pivot 54 against the pressure of the spring 57. The end portion of the lever 55 which lies outside the structure confined by the side plates 37, 37', has a hole, preferably of rectangular cross section (Fig. 9), through which extends a marker 59 of similar cross section at its central portion. The lower portion of the marker 59 is V-shaped in one direction (Fig. 3) and forms a shoulder against which bears one end of a spring 59', the other end of which bears against the lever 55 so as to hold the marker in its normal position shown in Fig. 3, in which position the nut 59'' screwed on the upper screw-threaded portion of the marker rests on the lever 55. The lower edge of the V-shaped portion of the marker is intended to make the desired record on the recording strip 32 mounted on the drum 29 and is transverse to the direction in which said strip travels.

The operation of our speed-and mileage-recording device is as follows: The proportions between the pinion 44, the worm 45 and the wheels of the vehicle are such that for every mile the vehicle has been traveling (forward) the pinion 44 with its shaft 43 will have performed one complete revolution. As the disk 50 revolves with the shaft 43 (in the direction shown by the arrow in Fig. 3), the pin 50' will once in every revolution engage the lever 51 and swing it on its pivot 51* until the pin enters the slot 51', whereupon the lever 51 will be pulled back quickly by the action of the spring 52 to its original position (in contact with the stop 53). When the pin 50 on its further travel again reaches the lever 51 (this time from the rear of the lever), it can pass freely without affecting the position of the lever, owing to the provision of the slot 51'' in the path of the pin. On its swing away from the stop 53, the lever 51 will come in contact with the lower portion of the arm 58, which latter will yield by swinging on its pivot 55', and thus allow the lever 51 to pass. On the return swing of the lever 51, however, the arm 58 cannot yield, but will be lifted, causing the lever 55 to swing on its pivot 54, and this again will cause the marker 59 to strike against the recording strip, or rather against the protective strip 32'. The loose, yielding connection between the marker 59 and the lever 55 will prevent the marker from striking too hard on the drum 29, the spring 59' returning the marker to the normal position with respect to the lever 55. By means of the carbon paper interposed between the protective strip and the recording strip, each blow delivered by the marker 59 on the drum 29, and therefore each mile traveled by the vehicle, will be recorded by a transverse line on the recording strip 32. As

described above, the drum 29 is rotated continuously by the clock 20, and the recording strip will therefore show in the particular space or row (I), a succession of transverse lines representing the number of miles traveled. Assuming that the vehicle has been traveling continuously, the distance between two successive lines will indicate the time consumed for each mile of travel; if stops have been made, these will be recorded in another space or row, as will be described below, and in this case of course the time during which the vehicle has been stopping, will have to be deducted in order to find the time consumed for a certain distance of travel.

The second space (II) of the recording strip will indicate at what time, and for what length of time the vehicle has been running during the day, that is during the 24 hours. This is accomplished by a device quite similar to the one just described (see Fig. 4). On the shaft 46 is mounted a bevel gear 60 in mesh with a bevel gear 61 of the same size, which latter is rigidly mounted on a shaft 62 extending through, and supported by, the side plates 37, 37', in the same manner as shaft 43. A nut 62' on one side and the gear 61 on the other, prevent lateral movement of the shaft 62. Rigidly mounted on this shaft is a disk 63 having a pin 64 adapted to engage at times a lever 65 pivoted at 65* and having slots 65', 65'', a spring 66 tending to hold the lever 65 normally against a stop 67. When the lever 65 is swung on its pivot by the pin 64, it will first cause to yield, and on its return movement lift, an arm 68 pivotally connected at 69 with a lever 70 pivoted at 54 and held by a spring 71 in its normal position against the stop 56. The lever 70 is slotted to receive the arm 68 which is held in its normal position shown in Fig. 4, by a spring 72, and which has a short face 68' bearing against the lever 70, as has been described above in detail in connection with the arm 58 and the lever 55 (Fig. 3). The free end of the lever 70 is provided with a marker 73 having a spring 73' and a nut 73'' similar to those of the marker 59. The operation of this recording device, which will make its marks in space or row II, is exactly the same as described above in connection with row I, except that, owing to the different ratio of gearing, the marker of row II will be operated much oftener than that of row I. A transverse line will be marked in row II at every revolution of bevel gear 61, and this may be so connected that one such mark will be made in row II after the completion of every one-twentieth of a mile. The marks or lines in row II will be so close together during each period of continuous travel that they will coalesce or run together so as to

appear as a wide solid black line covering practically the whole width of row II, as shown in Fig. 16. When the vehicle is not traveling, no record will, of course, be made in rows I or II of the record strip, so that the white spaces in row II will show the time the vehicle has been standing, while the heavy black lines will indicate the exact time it has been running.

10 The next two spaces of the record strip, III and IV, serve to mark therein the time spent in loading and unloading respectively. The mechanism for recording the loading time is shown in detail in Fig. 5 and is constructed as follows: To the shaft 62 is secured rigidly a disk 74 provided on one side with a pin 75 adapted to engage and operate at times, a lever 76 pivoted at 65* and having two slots 76' and 76''. Normally, this lever is held against the stop 67 by a spring 77, but when actuated by the rotating pin 75 the lever will engage a short lug or dog 78 pivoted at 78' to an arm 79 which is itself pivoted at 79' in two adjoining partition strips 40. The dog 78 is held in the normal position with respect to the arm 79 by a spring 78''. One end of the arm 79 is adapted to engage at times a stop 80, while its other end fits into a recess provided in a slide 81 guided by two guides 82, 83 secured to one of the partition strips 40. The end of the arm 79 engaging this recess is slightly beveled off so as to prevent binding of the parts when they are moved. A spring 81' bearing against a projection on the guide 82 tends to push the slide 81 upward against a rod divided by an inclined cut 84'' into a slide 84 and a lever 84'. The slide 84 has at its lower face, in proximity to the cut 84'', a recess 84* adapted to be engaged at times by the upper portion of the slide 81; it is also provided at its end with a handle 84a by means of which it can be moved lengthwise, stationary guide pieces 85, 85', and 85'' and 83 serving to guide it properly. Projections 84b and 84c on the slide 84 will limit its movement in either direction by coming in contact with one or the other end face of the guide piece 85'. A spring 86 tends to hold the slide 84 in its normal (innermost) position, in contact with the lever 84'. The latter is pivotally supported at 54, a spring 87 held by a stationary bracket 87' tending to swing the lever 84' on its pivot against the slide 84. A marker 88 is secured rigidly to the end of this lever; the lower end of this marker is pointed so that it will, by coming in contact with the recording strip (or its protective strip), mark a dot on said strip, or, if this contact continues, it will mark, owing to the rotation of the drum 29, a line running lengthwise of the recording strip.

15 The operation of the loading-time recorder is as follows: At the moment of be-

ginning to load (the vehicle being of course stationary at the time), the handle 84a is pulled by the driver of the vehicle or other person in charge of the work. The slide portion 84, to which this handle is secured, 70 slides out against the tension of the spring 86 until its projection 84b comes in contact with the guide piece 85'. By this movement, the recess 84* of the slide portion 84 will have been brought over the upper end 75 of the slide 81, which latter will enter this recess under the pressure of the spring 81' and thus prevent the slide portion 84 from returning to its original position. As soon as the slide portion 84 has moved away from 80 the lever portion 84', this latter will swing on its pivot under the action of the spring 87 until the recording point of the marker 88 has come in contact with the recording strip (or rather the protective strip), marking 85 a line in space III of said strip (as shown in Fig. 16), as long as the loading operation continues, that is to say, as long as the vehicle remains stationary. As soon as the vehicle begins to travel, the marking mechanism will be released from engagement with the recording strip in the following manner: The rotation of the wheels is communicated by means of the flexible shaft, shaft 46, and gears 60, 61 to the shaft 95 62. During the first revolution of this shaft, the pin 75 on the disk 74 will engage and swing the lever 76 on its pivot 65*, the dog 78 allowing the lever to pass by yielding to the right. When the pin 75 has reached the 100 slot 76' on the lever 76, the latter will return to its original position under the action of the spring 77. As described above, the dog 78 cannot yield independently on the return movement of the lever 76, but will be 105 lifted by the latter, causing the arm 79 to swing on its pivot 79' and the slide 81 in engagement with said arm to be withdrawn from the recess 84* in the slide portion 84. Thus released, this slide portion 84 will 110 return to the position shown in Fig. 5, under the action of the spring 86, causing the lever portion 84' to swing slightly on its pivot 54, thus raising the marker 88 from the recording strip. At every revolution 115 of the shaft 62, the pin 75 will engage and swing the levers 76 and 79 and reciprocate the slide 81, but obviously this will not affect the slide 84 and lever 84' as long as they are in the inactive position illustrated 120 by Fig. 5.

The construction and operation of the mechanism for recording the time spent in unloading (space IV of the recording strip), is exactly the same as just described in connection with the loading-time recorder. Detailed description of this mechanism and its operation will therefore be superfluous. The slide portion 89 is provided with a handle 89a to be pulled out at the time the unload- 130

ing of the vehicle is begun, while the lever portion 89' will record, by means of the marker 90 mounted thereon, the time spent in unloading. In order to release the mechanism when the vehicle begins to travel again, we may employ a disk similar to disk 74; the construction is simplified, however, if the pin (75') corresponding to the pin 75 is simply mounted on the reverse side of the same disk (74) carrying the pin 75, as indicated by the dotted circle in Fig. 5. The recesses in the lever to be engaged by the pin 75' must then of course be located on that side of the lever which faces the disk 74.

In Fig. 6, we have illustrated in detail the mechanism for recording in space V of the recording strip, the number of trips performed by the vehicle in the course of 24 hours. A slide 91, provided with a handle 92 is adapted to move in a stationary U-shaped guide 93, stationary guiding strips 94, 94' holding the slide down in its proper position within the guide 93. Normally, the slide is held in its innermost position, with its widened outer position 91' against the guide piece 94', by a spring 95, one end of which is secured to the slide 91, while the other end is fastened to the guide 93. A slot 91" is provided in the slide 91, within which is pivotally secured at 96' a dog 96 normally held in the position shown in Fig. 6 by a spring 97. As will be seen from Figs. 6 and 13, the dog 96 is of such a shape that it can swing on its pivot in one direction, against the tension of the spring 97, but cannot yield in the other direction. Pivotally mounted at 98' is a lever 98 normally held against the stop 53 by a spring 99. The lower portion of this lever is adapted to be engaged at times by the dog 96, while its upper portion will engage at times a short arm 100 pivotally secured at 101 to a lever 102 pivotally supported at 54 by the side plate 37' and one of the partition strips 40. A spring 103 normally holds the arm 100 in the position shown in Fig. 6, while a spring 104 normally holds the lever 102 against the stop 56. The end of the lever 101 carries a marker 105 adapted to strike at times against the recording strip on the drum 29. The construction of the arm 100, lever 102 and marker 105 is identically the same as described above in connection with arm 58, lever 55, and marker 59.

This strip-recording device operates as follows: Every time the vehicle starts on a trip, the driver pulls out the slide 91 by means of the handle 92, the engagement of the dog 96 with the guiding piece 94' limiting the movement of the slide. The dog 96, unable to yield when coming in contact with the lower portion of the lever 98, will swing the latter on its pivot 98'. The upper portion of the lever 98 will pass the arm 100, this arm yielding by swinging on its

pivot 101. After the lug 96 has cleared the lower edge of the lever 98, this lever will swing back to its normal position, lifting the arm 100, now unable to yield, and causing by this action the marker 105 to mark a transverse line in the space V of the recording strip, as shown in Fig. 16. The slide 91, released, will return to its normal, innermost position, owing to the tension of the spring 95, the dog 96 now yielding when it comes in contact with the lever 98 and clearing the latter.

The entire mechanism is preferably enclosed in a casing 106 so as to keep out dust and to prevent any tampering with the mechanism or the recording strip. A door 107 (normally locked) is provided in the front of the casing, which will allow the drum 29 to be withdrawn at the end of the 24 hours, for the purpose of removing therefrom the recording strip with the record of the working day, and replacing it by a new strip for the following day.

Fig. 16 shows that on the recording strip which has been removed from the apparatus, will be found a complete record of the work accomplished by the vehicle for the 24 hours during which the recording strip was on the drum. From the time the vehicle has begun to receive its first load until it has returned to the starting point on its last trip, a record must be marked in any one of the three spaces II, III, and IV, that is, the vehicle must either be running and mark a heavy black line in space II, or, if it is standing for a time, there must be found for the standing period a mark either in space III or IV, that is to say, the standing time must have been spent either in loading or in unloading. If there is no record in rows III or IV corresponding to a blank space in row II, the driver must account for the time for which there is no record. It will be seen that by means of our recording device an exact record of the manner of using the vehicle will be obtained. This is of great advantage for the reason that it will induce greater efficiency on the part of the drivers, for they will know that they will not be able to waste time without detection. The recording strip may conveniently be made of sufficient width to note thereon an entry such as a résumé or total of the individual records or of data deduced from such records, such as for instance: mileage, time in service, time running, time standing, time loading, time unloading, loads, deliveries, average time of loading per load, average time unloading per load, etc. The mileage and speed recorded will not only indicate the distance traveled by the vehicle, but will also enable the owner to figure the average speed for each mile that the vehicle has been running continuously.

The casing containing our recording

130

mechanism may conveniently be placed in front of or near the driver's seat. In this case, the device will serve at the same time as an automobile clock, if the wall of the 5 casing is made transparent in front of the clock, so that the dial will be visible from the outside (Fig. 2). Preferably, the clock will also be arranged in such a way that it can be wound from the outside, without 10 necessitating the opening of the casing. Of course, it is not necessary to employ a complete clock (with hands and dial) for feeding the recording strip, but any clockwork or equivalent motor running with sufficient 15 uniformity of speed can be employed. While we have described the marking of the record strip by means of carbon paper, it will be obvious that we may employ other means, such as the well-known waxed 20 or paraffined paper, or a recording pencil or pen such as are used in meteorological recording instruments.

We claim as our invention:

1. A recording device for carriages, comprising a clockwork or like motor for feeding a record strip, means operatively connected with the carriage, for recording, on said strip, the distance traveled, a device, under control of the operator, for making on said strip a record of the time during which the carriage is being loaded, another device, likewise under the control of the operator, for making on said strip a record of the time during which the carriage is 30 being unloaded, means, operated by the starting of the carriage, for throwing said devices out of action, and means, under control of the operator, for marking on said strip, the number of trips and the time each 35 trip was begun.

2. A recording device for carriages, comprising a clockwork or like motor for feeding a record strip, means operatively connected with the carriage, for recording, on 40 said strip, the distance traveled, a device, under control of the operator, for marking on said strip a record of the time during which the carriage is being loaded, another device, likewise under the control of the 45 operator, for making on said strip a record of the time during which the carriage is being unloaded, and means, operated by the starting of the carriage, for throwing out of 50 action the devices which record the loading 55 and the unloading time.

3. A recording device for carriages, comprising a clockwork or other motor for feeding a record strip, means, operatively connected with the carriage, for making a mark 60 on said strip whenever the carriage in its travel has completed a unit of distance, a device, under control of the operator, for making on said strip a record of the time during which the carriage is being loaded, 65 another device, likewise under the control of

the operator, for making on said strip a record of the time during which the carriage is being unloaded, and means, operated by the starting of the carriage, for throwing out of action the devices which record the 70 loading and the unloading time.

4. A recording device for carriages, comprising a record-carrier, a motor for imparting a continuous motion to said record-carrier, a device for recording on a strip 75 borne by said carrier the distance traveled, another device, under the operator's control, for recording on said strip the time spent on some operation performed while the carriage is standing, and means, operated by the starting of the carriage, for throwing the last-named device out of action.

5. A recording device for carriages, comprising a device, under the operator's control, for making a separate record of the 85 time spent on some operation performed while the carriage is standing, and means, operated by the starting of the carriage, for throwing the last-named device out of action.

6. A recording device for carriages, comprising a plurality of independent devices, under the operator's control, for recording individually, the time spent on different operations performed while the carriage is 95 standing, and means, operated by the starting of the carriage, for throwing any and all of the last-named devices out of action.

7. A recording device for carriages, comprising a clockwork or like motor for feeding a record strip, means, operatively connected with the carriage, for making a practically continuous mark on said strip while the carriage is running, and also far making a mark on said strip whenever the carriage 105 in its travel has completed a unit of distance, a device, under the operator's control, for recording the time spent on some operation performed while the carriage is standing, and means, operated by the starting of 110 the carriage, for throwing the last-named device out of action.

8. A recording device for carriages, comprising a clockwork or like motor for feeding a record strip, means, operatively connected with the carriage, for making a practically continuous mark on said strip while the carriage is running, and a device, under the operator's control, for recording on said 115 strip the time spent on some operation performed while the carriage is standing.

9. A recording device for carriages, comprising a clockwork or like motor for feeding a record strip, means, operatively connected with the carriage, for making a practically continuous mark on said strip while the carriage is running, a device, under the operator's control, for recording the time spent on some operation performed while 125 the carriage is standing, and means, oper- 130

ated by the starting of the carriage, for throwing the last-named device out of action.

10. A recording device for carriages, comprising a normally inactive device for recording the time spent on some operation performed while the carriage is standing, means, under the operator's control for setting said device in its recording position, 10 and means, operated by the starting of the carriage, for returning said device to its inactive position.

11. A recording device for carriages, comprising a normally inactive device for recording the time spent on some operation to be performed while the carriage is standing, means, operatively connected with the carriage, for bringing said recording device back to its inactive position when the carriage is traveling, means, under the operator's control, for bringing the device to its active or recording position, and means, whereby the recording device, after it has been brought to its active position, will be 25 locked in such position while the carriage is standing.

12. A recording device for carriages, comprising a clockwork or like motor for feeding a record strip, a lever provided with a 30 marker for making a record on said strip, a spring-pressed arm pivoted to said lever and having a limited swinging movement thereon, another lever adapted to engage said arm and to swing it first independently 35 of its lever in one direction and subsequently with its carrying lever, to cause the latter to produce a record, and rotary means, operatively connected with the carriage, for swinging the second-named lever in one 40 direction and subsequently releasing it to allow its return.

13. A recording device for carriages, comprising a clockwork or like motor for feeding a record strip, a spring-pressed lever 45 provided with a marker for making a record on said strip, a spring-pressed arm having a limited movement relatively to said lever, another lever adapted to engage said arm and to move it first independently of 50 its lever in one direction and subsequently with its carrying lever, to cause the latter to produce a record, a spring tending to return the second-named lever to its initial 55 position, and rotary means, operated by the travel of the carriage and provided with a pin adapted to engage and swing the said second-named lever, the latter being provided with an opening in the return path of 60 said pin, and with another opening adapted to allow the passage of said pin after the lever has been swung by the action of the said pin.

14. A recording device for carriages, comprising a clockwork or like motor for feeding a record strip, a movable carrying mem-

ber provided with a marker for making a record on said strip, an arm carried by said member and capable of a limited movement relatively thereto, another movable member adapted to move first in one direction and 70 then in the opposite direction and to move the said arm independently of its carrying member during the forward movement of said second-named member, and with its carrying member during the return movement of said second-named member, to cause the marker to produce a record, and means, operated by the travel of the carriage, for actuating said second-named member.

15. A recording device for carriages, comprising a clockwork or like motor for feeding a record strip, a movable carrying member provided with a marker for making a record on said strip, an arm carried by said member and capable of a limited movement 80 relatively thereto, another movable member adapted to move first in one direction and then in the opposite direction and to move said arm independently of its carrying member during the forward movement of 85 said second-named member, and with its carrying member during the return movement of said second-named member, to cause the marker to produce a record, and a rotary pin, operated by the travel of the carriage, the second-named movable member being provided with a portion extending in 90 the forward path of said pin so as to cause the latter to move said member forward, the latter being also provided with a clearance 100 to allow said pin to pass freely on its return movement, and being further provided with another clearance to register with said pin after the second-named member has been shifted by the pin, allowing said member to 105 return to its normal position.

16. A recording device, comprising a clockwork or like motor for feeding a record strip, a movable member, a marker mounted to slide on said member toward or 110 from the record strip, but held against turning relatively to said member, said marker having a marking edge transverse to the path of the record strip, a spring tending to project the marker from said member, 115 and means for operating said member.

17. A recording device, comprising a clockwork or like motor for feeding a record strip, a lever carrying a marker for producing a record on said strip, a spring tending to throw said lever into the marking position, a slide normally alining and contacting with said lever and holding it 120 in its inactive position, another slide movable transversely of the first-named slide, to 125 lock the latter in the position in which it releases the marking lever, and means for controlling said locking slide.

18. A recording device for carriages, comprising a clockwork or like motor for feed- 130

- ing a record strip, a lever carrying a marker for producing a record on said strip, a spring tending to throw said lever into the marking position, a slide normally alining and contacting with said lever and holding it in its inactive position, another slide movable transversely of the first-named slide and spring-pressed toward it to lock it in the position in which it releases the marking lever, and means, operated by the travel of the carriage, for withdrawing the locking slide and allowing the other slide to return to its normal position and restoring the marking lever to its inactive position.
19. A recording device for carriages, comprising a clockwork or like motor for feeding a record strip, a spring-pressed lever carrying a marker for producing a record on said strip, a movable member, under the operator's control, for normally holding said lever in its inactive position, means for locking said member in the position in which it releases said lever, and means, operated by the travel of the carriage, for withdrawing said locking means and causing the marking lever to be restored to its inactive position.
20. A recording device for carriages, comprising a clockwork or like motor for feeding a record strip, a movable marker for producing a record on said strip, a movable member normally holding said marker in its inactive position but adapted to be moved by the operator to release said marker, means for locking said member in its releasing position, and means, operated by the travel of the carriage, for withdrawing said locking means and causing the marker to be restored to its inactive position.
21. A recording device for carriages, comprising a clockwork or like motor for feeding a record strip, a movable marker for producing a record on said strip, a movable member normally holding said marker in its inactive position but adapted to be moved by the operator to release said marker, means for locking said member in its releasing position, a withdrawing lever in operative engagement with said locking means, a spring-pressed dog carried by said lever and capable of a limited movement relatively thereto, an actuating lever adapted to engage said dog, and means, operated by the travel of the carriage, for rocking said actuating lever.
22. A recording device for carriages, comprising a clockwork or like motor for feeding a record strip, a movable marker for producing a record on said strip, a movable member normally holding said marker in its inactive position but adapted to be moved by the operator to release said marker, a spring-pressed slide for locking said member in its releasing position, a withdrawing lever engaging said slide, a dog having a limited movement relatively to said lever, an actuating member adapted to engage said dog and move the slide away from its locking position, and means, operated by the travel of the carriage, for moving said actuating member.
23. A recording device for carriages, comprising a clockwork or like motor for feeding a record strip, a movable marker for producing a record on said strip, a movable member normally holding said marker in its inactive position but adapted to be moved by the operator to release the said marker, a spring-pressed member for locking the first-named member in its releasing position, a withdrawing member engaging said locking member, a dog carried by said withdrawing member and having a limited movement relatively thereto, an actuating spring-pressed lever adapted to engage said dog, and a rotary pin, adapted for operation by the travel of the carriage, to engage said actuating lever and swing it in one direction, said actuating lever having a clearance to allow the passage of said pin when the lever has been swung a certain distance, so as to allow the lever to return under the influence of its spring, and said lever also having another clearance to allow the passage of said pin on its return movement, after the lever has resumed its original position.
24. A recording device, comprising a clockwork or like motor for feeding a record strip, a spring-pressed lever carrying a marker and provided with a beveled end, a slide alining with said lever in one position thereof and movable into and out of contact therewith, the contacting end of said slide being beveled to correspond to the adjacent lever end, and means for controlling the position of said slide.
25. A recording device, comprising a clockwork or like motor for feeding a record strip, a spring-pressed lever carrying a marker and provided with a beveled end, a slide alining with said lever in one position thereof and movable into and out of contact therewith, the contacting end of said slide being beveled to correspond to the adjacent lever end, another slide movable transversely of the first-named slide and adapted for locking engagement therewith, a withdrawing lever engaging said locking slide, a spring for pressing the locking slide toward the first-named slide, a spring-pressed dog carried by said withdrawing lever and capable of a limited pivotal movement relatively thereto, and an actuating member adapted for engagement with said dog.
26. A recording device for carriages, comprising a clockwork or like motor for feeding a record strip, a spring-actuated lever provided with a marker for making a rec-

ord on said strip, a spring-pressed arm pivoted to said lever and having a limited swinging movement thereon, another lever adapted to engage said arm and to swing it 5 first independently of its lever in one direction and subsequently in the opposite direction with its carrying lever, to cause the lat-

ter to produce a record on said strip, and means for actuating the second-named lever.

In testimony whereof, we have signed this 10 specification.

WILLIAM MURRAY.
EDWARD C. BANTA, JR.
